US00D950420S

(12) **United States Design Patent** (10) **Patent No.:** **US D950,420 S**
(45) **Date of Patent:** **** May 3, 2022**

(54) **ALL-TERRAIN VEHICLE**

(71) Applicant: **ZHEJIANG TAOTAO VEHICLES CO., LTD.**, Lishui (CN)

(72) Inventors: **Guidong Lou**, Lishui (CN); **Jie Xu**, Lishui (CN); **Junhui Li**, Lishui (CN); **Weihao Liu**, Lishui (CN); **Yali Ying**, Lishui (CN)

(73) Assignee: **ZHEJIANG TAOTAO VEHICLES CO., LTD.**, Lishui (CN)

(**) Term: **15 Years**

(21) Appl. No.: **29/775,419**

(22) Filed: **Mar. 23, 2021**

Related U.S. Application Data

(62) Division of application No. 29/652,135, filed on May 18, 2020, now Pat. No. Des. 926,636.

(57) **CLAIM**

The ornamental design for an all-terrain vehicle, as shown and described.

DESCRIPTION

FIG. 1 is a front perspective view of an all-terrain vehicle embodying our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings illustrate portions of the all-terrain vehicle that form no part of the claimed design.

1 Claim, 8 Drawing Sheets
